[57] CLAIM

The ornamental design for an airplane, as shown and described above.

DESCRIPTION

FIG. 1 is a side elevational view of an airplane depicting our new design;

FIG. 2 is an upper front perspective view thereof;

FIG. 3 is a bottom perspective view thereof;

FIG. 4 is a top plan view thereof; and

FIG. 5 is a front elevational view thereof.

The broken line disclosure of landing gears is for illustration purposes only and does not form part of the claimed design.
